UNITED STATES PATENT OFFICE.

WILLIAM S. ELLIOT, OF NORTHAMPTON, MASSACHUSETTS, ASSIGNOR TO PRO-PHY-LAC-TIC BRUSH COMPANY, OF NORTHAMPTON, MASSACHUSETTS, A CORPORATION OF MASSACHUSETTS.

SHIFTING DEVICE FOR POSITIONING MECHANISM FOR BRUSH MACHINES.

Application filed February 24, 1925. Serial No. 11,096.

The present invention has for its object an improvement in the brush machine shown in the patent to Herman M. Schwartz, No. 1,125,187, dated January 19, 1915, in which the general features of the machine are fully shown and described. In that machine there is a travelling carrier in the form of an endless chain made up of a series of brush holders to which the brush backs to be drilled and tufted are attached. There is also automatic mechanism including two cams on a cam shaft which move the travelling carrier horizontally and vertically to position the brush lengthwise and crosswise, and mechanism for revolving the travelling carrier in its orbit after the completion of each brush or pair of brushes. The mechanism for revolving the travelling carrier is conveniently shown as the shifting mechanism, as it shifts the completed brush out of position and an unfilled brush blank into position to be drilled and tufted. The present invention has for its object to improve this shifting mechanism and render it simpler, quicker, quieter and more reliable in its operation.

In the following description the details of the machine except those which are essential to an understanding of the improved shifting mechanism have not been shown or described since reference may be made to the said patent to Schwartz for further information.

The invention will be fully understood from the following description when taken in connection with the accompanying drawings, and the novel features thereof will be pointed out and clearly defined in the claims at the close of this specification.

Fig. 1 is a side elevation of the positioning mechanism of a brush machine embodying my invention.

Fig. 2 is a rear elevation of the machine.

Fig. 3 is an enlarged sectional view taken on line 3—3 of Fig. 1.

Fig. 4 is a section taken on line 4—4, Fig. 3.

Referring now to the drawings:

At A is shown the drill and at B the tufting of a brush machine of the type in question. The travelling carrier, which in this machine is in the form of an endless chain, is designated C and is supported on brackets D and E which are themselves carried on the

vertical slide F. The horizontal slide is shown at G and the cams which operate the slides are shown at H and I respectively, these cams being located on the cam shaft 11. It will be understood that the rotation of the cam shaft 11 turns the cams H and I and lifts the carrier and moves it horizontally in accordance with the pattern of the holes in the brush back. It will also be understood that when each brush has been drilled or filled, as the case may be, it is necessary to move the travelling carrier in its orbit to bring other brush backs into operating position; also that before this movement takes place, the carrier must be unlocked and after it takes place it must be relocked so that the registration of the brush backs with regard to the drill and tufting will be perfect. It will be understood that the mechanism just described is not novel having been shown in the said patent to Schwartz, and forms no part of the present invention except in combination with other features.

The shifting mechanism will now be described.

Referring now to Figs. 1 and 2, at 12 is shown a finger having an inclined end a. This finger is secured to the rear end of the cam shaft 11 and revolves with it. In the path of the inclined surface of the finger 12 is one end b of a bell crank 13 pivoted at 14 to the frame of the machine. The arm 12 therefore engages the inclined surface b on the bell crank 13 once for each revolution of the cam shaft 11 and swings the bell crank as it passes. The other arm of the bell crank is connected by a link 15 to a swinging arm 16 pivoted at 17 to the frame of the machine. This swinging arm 16 has an extension 18 below the pivot 17 to which is secured a spring 19 which serves to hold the upper end of the swinging arm 16 to the right, as shown in Fig. 2.

Crosswise of the rear of the machine is a rotatable clutch shaft 20, on which is loosely mounted a constantly running sprocket wheel 21, driven by a chain 22 from a sprocket wheel 23, secured to some constantly running shaft of the machine. The hub 9 of the sprocket wheel 21 forms one part of a roll clutch of ordinary construction, rollers being shown at 25. Fast to the shaft 20 is the clutch member 26 on the hub 8 of which is loosely mounted the shell 27 of the clutch.

An arm 28 secured to the clutch member 26 is connected by a spring 29 to a stud 30 on the shell 27. The spring 29 tends to rotate the shell relatively to the clutch member 26. 5 The shell 27 is provided with a projection 31 having a face *c* to engage the upper end of the swinging arm 16 which has already been described.

The structure described is such that when 10 the finger 12 on the cam shaft 11 strikes the surface *b* on the bell crank 13 it pulls the upper end of the swinging arm 16 out from under the stop surface *c* on the clutch shell 27, and the spring 29 then rotates the shell 15 enough to cause the rollers to ride up on the inclined surfaces 7 of the member 26 and connect said member with the sprocket 21 so that the shaft 20 will be revolved by said sprocket. This movement continues for one 20 revolution but is stopped by the surface *c* on the shell striking the upper end of the arm 16 which has in the meantime been swung back into place by the spring 19.

On the left hand end of the clutch shaft 25 20 is a crank arm 32 connected by a crank pin 33 to a block 34. This block is forked and connected by a pivot 35 to a link 36. The other end of the link is likewise connected by a vertical pivot 37 to an arm 38. 30 The vertical pivots 35 and 37 allow for the horizontal movement of the carrier lengthwise of the brush which would otherwise cramp or bend the connections between the crank arm 32 and the travelling carrier.

35 The arm 38 is connected to the locking lever 39 which is pivoted at 40 to the bracket E and operates the locking pins 41 which lock the chain in position so that each brush back is perfectly centered and held immovably during the operation of the drill and tufter. The locking lever 39 also operates 40 through the pin 42 and slotted link 43 and the shifting lever 44 which moves the chain by means of a pawl 45 engaging a ratchet 45 wheel 46 on the shaft 47 which carries the sprocket wheel for the chain.

As explained in the Schwartz patent previously mentioned, the first movement of the locking lever to the left, as shown in Fig. 1, 50 unlocks the chain, while further movement moves the shifting lever 44 and causes the pawl 45 to revolve the chain and shift the brush holders.

The shifting mechanism described herein 55 and embodying the present invention has proved in actual service to be much more satisfactory than the mechanism shown in the said Schwartz patent, as it is much more reliable in operation and does not subject the machine to a violent shock when it operates. It is also less likely to get out of order and is much quieter.

I claim—

1. In a brush machine having a travelling blank carrier, in combination, a shaft, mechanism for driving the carrier, a constantly rotating member, a clutch connecting said rotating member and said driving mechanism, and means on the shaft for controlling the clutch to connect the rotating member and the driving mechanism. 65

2. In a brush machine having a travelling carrier, in combination, a shaft, mechanism for shifting the carrier including a constantly rotating member, a crank, a clutch operatively connecting said crank and the rotating member, and mechanism controlled by the shaft for actuating the clutch once for each revolution of the shaft. 75

3. In a brush machine having a travelling blank carrier, in combination, a shaft, mechanism for shifting the carrier including a constantly rotating member, a crank, a finger on said shaft, a clutch connecting the crank to said rotating member, and mechanism operated by said finger for operating the clutch each time it is engaged by said finger. 80

4. In a brush machine having a travelling carrier, in combination, a shaft, mechanism for shifting the carrier including a constantly rotating member, a crank, a roller clutch connecting said crank to the constantly rotating member, a stop for one member of the clutch, an arm adapted to engage said stop, and a finger on said shaft adapted to cause movement of said arm to engage said stop thereby permitting the clutch to connect said crank to said constantly rotating member. 90

5. In a brush machine having a travelling blank carrier, in combination, a shaft, a constantly rotating member having a hub forming one member of a roller clutch, a clutch shaft having a clutch member thereon, a crank on said clutch shaft, driving means for the carrier operated by said crank, a stop carried by said clutch member on the clutch shaft, a finger mounted on said shaft, and means actuated by said finger for alternately stopping and releasing the clutch member thereby actuating said driving means once for each revolution of the shaft. 105

6. In a brush machine having a travelling carrier, means for intermittently shifting said carrier and comprising a driven clutch member, a driving clutch member, a reciprocating member connected to the driven clutch member for shifting said carrier, a rotary shaft, and means automatically controlled thereby for intermittently connecting said clutch members. 115

In testimony whereof I affix my signature.
WILLIAM S. ELLIOT.
